UNITED STATES PATENT OFFICE.

GEORGE V. SCHLINK, OF PEORIA, ILLINOIS.

DESIGN FOR A VEHICLE-DOOR HANDLE.

60,576.

Specification for Design.

Patented Mar. 7, 1922.

Application filed June 30, 1921. Serial No. 481,668. Term of patent 3½ years.

To all whom it may concern:

Be it known that I, GEORGE V. SCHLINK, a citizen of the United States, residing at Peoria, in the county of Peoria and State of Illinois, have invented a new, original, and ornamental Design for Vehicle-Door Handles, of which the following is a specification, reference being had to the accompanying drawing, forming part thereof.

My invention relates more particularly to hand pieces or handles which are adapted to be attached and forming a part of the latch operating lever of an automobile door.

In the drawing:

Fig. 1 is a plan view of a handle made in accordance with my design.

Fig. 2 is a side view of handle shown in Fig. 1.

Fig. 3 is a front view of Fig. 2.

Fig. 4 is bottom plan view.

I claim:

The ornamental design for a vehicle door handle, as shown.

GEORGE V. SCHLINK.
